DESIGN FOR A GLOVE

Kay Fuchs, New York, N. Y.

Application March 18, 1937, Serial No. 68,245

Term of patent 3½ years

To all whom it may concern:

Be it known that I, Kay Fuchs, a citizen of the United States of America, residing in Manhattan, county and State of New York, have invented a new, original, and ornamental Design for a Glove, of which the following is a specification, reference being had to the accompanying drawing, forming part thereof, wherein,

The design is characterized by a single inner palm seam, in combination with the stitchings on the glove, as shown.

I claim:

The ornamental design for a glove, substantially as shown and described.

KAY FUCHS.
